[57] CLAIM

The ornamental design for a combined video camera and tape recorder, as shown and described.

DESCRIPTION

FIG. 1 is a front and left-side perspective view of a combined video camera and tape recorder showing our new design;

FIG. 2 is a rear and right-side perspective view thereof, shown with the viewfinder rotated 90° from FIG. 1;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and

FIG. 8 is a bottom plan view thereof.
The viewfinder is rotatably movable relative to the body of the combined camera and tape recorder.
